UNITED STATES PATENT OFFICE.

RICHARD S. IRVINE, OF SAN FRANCISCO, CALIFORNIA.

SELECTIVE ORGAN-PLAYER MECHANISM.

1,331,506.

Specification of Letters Patent. Patented Feb. 24, 1920.

Application filed April 26, 1916. Serial No. 93,616.

To all whom it may concern:

Be it known that I, RICHARD S. IRVINE, a citizen of the United States, residing at the city and county of San Francisco, have invented certain new and useful Improvements 5 in Selective Organ-Player Mechanism; and I do declare the following to be a full, clear, and exact description of the same, reference being had to the accompanying drawings, 10 and to the characters of reference marked thereon, which form a part of this application.

This invention relates to improvements in automatic player musical instruments arranged to be operated electrically, the object 15 of the invention being to produce a multiple tracker board mechanism for the purpose wherein one mechanism may be thrown into or out of action, and another simultaneously 20 likewise thrown out of or into action and means whereby the one mechanism may be independently operated to position the music sheets thereon while the other mechanism is in operation. The demand for this type of 25 mechanism has been greatly increased by the present popular use of automatic musical instruments in connection with moving picture theaters and other show houses where it is desired to play different pieces of music to 30 fit the different scenes being enacted on the curtain or stage.

By the use of my improved mechanism, an electrically operated and controlled musical instrument can be readily adapted for this 35 purpose.

While the invention, as at present advised, is especially adapted for use in connection with pipe organs, still in practice it could as well be adapted for use in other connections. 40 For the purpose of the present illustration however, we will consider the same as used in place of or in connection with the keyboard used in connection with pipe organs for operating the various valves and stops, 45 the present invention especially relating to their operation by electrically controlled means.

A further object of the invention is to produce a simple and inexpensive device and yet 50 one which will be exceedingly effective for the purposes for which it is designed.

These objects I accomplish by means of such structure and relative arrangement of the parts as will fully appear by a perusal 55 of the following specification and claims.

In the drawings similar characters of ref-

erence indicate corresponding parts in the several views.

Figure 1 is a front elevation showing the multiple tracker board mechanism and the 60 selective and controlling parts in operative connection therewith.

Fig. 2 is a sectional view taken on a line X—X of Fig. 1.

Referring now more particularly to the 65 characters of reference on the drawings, I will let the numeral 1 designate the keyboard and the numeral 2 any suitable framework for supporting my improved mechanism.

For the purpose of the present illustration I have shown a double tracker board mechanism in which the numeral 3 designates the music sheet carrying roll of one mechanism and the numeral 4 designates the take up 70 roll of the same mechanism while the numeral 5 designates the carrying roll of the other mechanism and the numeral 6 the take up roll thereof. Between the rolls 3 and 4 is a tracker board mechanism which in my improved invention consists primarily of a roller 7 mounted in spring pressed pivoted arms 8 whereby the roller 7 may be moved away from the music sheet 9 against a back stop 10 or may be moved into engagement 75 with the sheet 9 against limiting stops 11. One of the stops 11 is connected by a wire 12 with an electrical contact switch blade 13 positioned at a definite point and for a purpose as will presently appear. The arm 8 80 and point 11 would of course be suitably insulated from the framework 2 by insulation 11^a.

Mounted on and insulated from a supporting beam 14 are a plurality of spring 95 fingers 15 arranged to frictionally engage the music sheet 9 as it is moving over the roller 7 so that as the perforations cut in said sheet 9 move adjacent the roller 7 these spring fingers 15 will project through the 100 perforations and contact with the roller 7 whereby an electrical circuit will be completed to operate the musical instrument in a manner as will presently appear.

The spring fingers 15 may be provided 105 with curved cams or any other suitable means at their ends for projecting through the perforations in such a manner as to avoid any possibility of catching and tearing the sheet 9 when passing into or out of a perforation.

Between the rollers 5 and 6 are members

16, 17, 18, 19, 20, 21, 22, 23, and 24 of similar structure to the members 7 to 15 respectively.

My improved invention embodies especially the following features, namely:

5 A forward operating mechanism for the music sheets wherein one sheet is operated forward for playing the musical instrument while the other one is in inoperative position; a means for rewinding the inoperative 10 sheet while the other sheet is in operation; and a means for moving the inoperative sheet forward while the other sheet is in operation to position it at any given selection, which forward movement may be had without 15 operating the musical instrument.

These features very readily subdivide themselves into separate parts and I will therefore describe each in order. Describing first the operating mechanism for the 20 music sheets wherein one sheet is operated forward for playing the musical instrument while the other one is in inoperative position, the numeral 25 designates the shaft for operating the roller 4 and the numeral 26 the 25 shaft for operating the roller 6. On the shafts 25 and 26 are gears 27 and 28 respectively meshing with pinions 29 and 30 mounted on shafts 31 and 32, this latter mechanism being for the purpose of reducing the speed.

30 Keyed to the shaft 31 are two sprocket wheels 33 and 34, the sprocket wheel 33 being of a larger size than the sprocket wheel 34, and similarly, on the shaft 32 are sprocket wheels 35 and 36. The sprocket wheel 34 is 35 connected by a chain 37 with the sprocket wheel 38 turnable on the shaft 39 driven by the driving motor 40, such sprocket 38, having a clutch face 41. A chain 42 connects the sprocket 34 with the sprocket 43 40 turnable on the shaft 39 and having a clutch face 44, all for a purpose as will appear. The numerals 45, 46, 47, 48, 49 and 50 indicate parts on the other mechanism similar to the parts 37, 38, 41, 42, 43 and 44.

45 The numeral 51 designates a selecting lever mounted at a point adjacent the keyboard 1 and arranged to throw either the roller 4 or 6 into operative position to advance the corresponding music sheet and to simultaneously discontinue the operation of the other roller and its music sheet. This is accomplished by means of the following structure, namely:

50 A link 52 connects the lever 51 with the bell crank 53 which bell crank is connected at its end by a link 54 with bell crank 55. Such bell crank 55 connects at its other end with a push rod 56 common to two levers 57 and 58. The lever 57 is connected with a 55 collar 59 slidably keyed to the shaft 39 and having a clutch 60 arranged to engage the clutch face 41. The lever 58 is connected with a collar 61 keyed to the shaft 39 and provided with a clutch 62 arranged for engagement with the clutch face 47.

Assuming that the roller 4 is to be thrown into operation to draw the music sheet off the roller 3 and over the roller 7 the lever 51 would then be moved to the left, which through the medium of the link mechanism 50 described will push the push rod 56 to the left and operate the lever 57 so as to move the clutch 60 into engagement with the clutch face 41 on the sprocket wheel 38. With this operation the push rod 56 will pull on the lever 58 so as to move it to that position in which the clutch 62 will be entirely free from any possibility of engagement with the clutch face 47 on the sprocket 46. When the clutch 60 is engaged with the face 41, the shaft 39 being rotated by the motor 40, this will rotate the sleeve 59, sprocket 38, and through the medium of the chain 37, will rotate the sprocket 33 and the shaft 31. Thus the pinion 29 will drive the gear 27, shaft 25 and roller 4 to advance the music sheet 9.

When the music sheet 9 is being advanced over the roller 7 by means of the operation just described it becomes necessary with such advancement to make electrical connections 90 between the roller 7 and the fingers 15, so that as the fingers 15 contact with the roller 7 through the perforations in the sheet 9, suitable mechanism may be thrown into operation to play the musical instrument, and this 95 is accomplished as follows:

When the lever 57 is thrown over to engage the clutch 60 with the clutch face 41 a contact point 63 on the said lever 57 is moved into engagement with the switch blade 13 100 whereupon a circuit can be completed as follows: A wire 64 connects the point 63 with a source of electrical energy 65 which may be of any desired or adaptable kind. Another wire 66 leads from the source 65 to 105 an electro magnet 67 from which another wire 68 leads to one of the fingers 15. The fingers 15 of course are insulated from the beam 14.

The electromagnet 67 being thus energized 110 by the closing of the circuit attracts the point 69 on the operating mechanism 70 of the musical instrument. No connection is shown between the member 70 and the valves and stops of the musical instrument since 115 this structure is common. It is of course understood that there is a separate circuit for each one of the fingers 15, each energizing a similar electromagnet which in turn attracts a member of the the same construction as the member 70, such members 70 being operatively connected to actuate the pipes of the organ in any manner common to the art.

When it is desired to cease taking up the 125 sheet 9 on the roller 4 and to take up the sheet 18 on the roller 6, the lever 51 is moved to the right. This acts on the lever 57 to throw the clutch 60 out of engagement with the clutch face 41 and also breaks the con- 130

tact between the points 63 and 13. At the same time the lever 58 is actuated to move the clutch 62 into engagement with the clutch face 47 and the points 72 and 22 into contact with each other. This, through the mechanism which corresponds to that mechanism described for throwing the roller 4 into action, throws the roller 6 into action and advances the sheet 18. The fingers 24 then act the same as described for the fingers 15 to complete the following circuit, namely:

From the source of electrical energy 65 through the wire 66, electromagnet 67, wire 68, wire 68^a to one of the fingers 24 thence through the roller 16, arm 17, point 20, wire 21, point 22, point 72, and wire 73 back to the source 65 thus throwing the electromagnet 67 into action and causing it to operate the members 69 and 70 as in a manner previously described.

By moving the lever 51 to vertical position the levers 57 and 58 will be so positioned that none of the mechanism for operating the musical instrument will be in driving relation with the shaft 39.

When the roller 4 is in operation and the roller 6 is not in operation for advancing the sheet 9 to operate the musical instrument, or vice versa or when neither of said rollers is being so operated, and it is desired to reposition the sheet 9 or the sheet 18 on the rollers 4 or 6 without rendering any music therefrom but merely for the purpose of bringing another selection into position ready to be played, this is accomplished by means of the following structure, namely:

The numeral 74 designates a small lever positioned adjacent the keyboard 1 and connected by a link 75 with a bell crank 76 which in turn is connected at its other end by a link 77 with another bell crank 78. This latter bell crank 78 is pivoted to a push rod 79. On one end of the push rod 79 is pivoted a lever 80 connected with a sleeve 81 slidably keyed to the shaft 39 and having a clutch 82 arranged to engage the clutch face 44 of the sprocket wheel 43. On the other end of the push rod 79 is connected a lever 83, which lever is connected with a sleeve 84 slidably keyed on the other side of the shaft 39 and provided with a clutch 85 arranged to engage the clutch face 50 on the sprocket 49. By throwing the lever 74 to the left, this, through the medium of the link mechanism shown, will move the push rod 79 to the right and thus actuate the lever 80 to move the clutch 82 into engagement with the clutch face 44 which will place the sprocket wheel 43 into driving relation with the shaft 39. This, through the medium of the chain 42 and sprocket wheel 34, will drive the shaft 31, pinion 29, gear 27, shaft 25 and roller 4 so as to rotate such roller 4 in its forward direction. Due to

the relative size of the sprockets 43 and 34 the roller 4 will be rapidly turned which will quickly move the sheet 9 over the roller 4 to any desired position and this can be accomplished while the roller 6 is being operated to actuate the musical instrument.

When the clutch 82 is engaged with the clutch face 44 the clutch 85 is simultaneously moved so as to be out of any possible engagement with the clutch face 50 so as not to affect the opposite mechanism, but when the roller 4 is being operated for playing the musical instrument the roller 6 can likewise be moved to position the sheet 18 thereon merely by moving the lever 74 to the right; or by having the lever 74 in vertical position neither of the clutches will be in engagement with its corresponding clutch face so as to allow of the operation of the mechanism for playing purposes only.

When it is desired to rewind the sheets 9 or 18 on their rollers 3 and 5 when the corresponding rollers 4 or 6 are not in action this can be accomplished by means of the following structure viz: A lever 86 is fulcrumed adjacent the keyboard 1 and is connected by a link 87 with a bell crank 88, the other end of said bell crank being connected by a link 89 with a bell crank 90, which bell crank 90 is connected with a push rod 91 connected at its ends with levers 92 and 93 respectively. The lever 92 is connected with a sleeve 94 slidably keyed on a shaft 95 and provided with a clutch 96, while the lever 93 is connected with a similar sleeve 97 slidably keyed on the shaft 95 and provided with a clutch 98. Secured on the shaft 95 is a sprocket wheel 99 connected by a chain 100 with a sprocket wheel 101 keyed to the shaft 39 whereby the shaft 95 rotates with the shaft 39. On the shaft 95 adjacent the sleeve 94 is a sprocket wheel 102 having a clutch face 103 which sprocket wheel 102 is connected by a chain 104 with a sprocket wheel 105 keyed to a shaft 106 which carries the roller 3. Similarly keyed to the shaft 95 adjacent the sleeve 97 is a sprocket wheel 107 having a clutch face 108, such sprocket wheel 107 being connected by a chain 109 with a sprocket wheel 110 keyed to a shaft 111 which carries the roller 5.

If it is desired to rewind the sheet 9 the lever 86 is moved to the left which, through the medium of the link mechanism described moves the push rod 91 to the right and throws the lever 92 so that the clutch 96 engages the clutch face 103 and operates the sprocket wheel 102, which, through the medium of the chain 104 advances the sprocket wheel 105 and the shaft 106 to wind the sheet 9 upon the roller 3. With the reverse action the clutch 98 is thrown into engagement with the clutch face 108 and operates the sprocket wheel 107 which, through the medium of the chain 109 operates the

4 sprocket wheel 110 to operate the shaft 111 to wind the sheet 18 upon the roller 5.

The motor 40 is driven by a suitable connection with the source of electricity 65 and 5 the time in which the music is played is controlled by regulating the speed of the motor with a resistance lever 112 which controls a suitable resistance 113 of any desired type.

10 While this specification sets forth in detail the present and preferred construction of the device, still in practice such deviations from such detail may be resorted to as do not form a departure from the spirit of 15 the invention, as defined by the appended claims.

Having thus described my invention what I claim as new and useful and desire to secure by Letters Patent is:

20 1. A music player mechanism comprising in combination a pair of note sheets, each mounted upon a carrier roller and a take-up roller, and being in operative connection with key actuating means, a common power driven shaft, clutches on the shaft and adapted to place the take-up rollers in operative connection with the shaft, and a common lever means for actuating said clutches whereby either sheet at any time may be 25 wound on its take-up roller and the key actuating means thereof simultaneously brought into play while the other take-up roller is disengaged from the power shaft and the key actuating means therefor held 30 from actuation, and a common means whereby at the same time either one of the rollers of the other sheet may be operatively connected with the power driven shaft to cause the note sheet to be wound on either of such 35 rollers and the key actuating means therefor held from operation.

key actuating means thereof simultaneously brought into play while the other take-up roller is disengaged from the power shaft and the key actuating means therefor held from actuation.

35 2. A music player mechanism comprising in combination a pair of note sheets, each mounted upon a carrier roller and a take-up roller, and being in operative connection with key actuating means, a common power driven shaft, clutches on the shaft and adapted to place the take-up rollers in operative connection with the shaft, a common lever means for actuating said clutches whereby either sheet at any time may be 40 wound on its take-up roller and the key actuating means thereof simultaneously brought into play while the other take-up roller is disengaged from the power shaft and the key actuating means therefor held 45 from actuation, and a common means whereby at the same time either one of the rollers of the other sheet may be operatively connected with the power driven shaft to cause the note sheet to be wound on either of such 50 rollers and the key actuating means therefor held from operation.

In testimony whereof I hereunto affix my signature.

RICHARD S. IRVINE.
